UNITED STATES PATENT OFFICE

2,467,622

DOOR LOCK

Ralph Kulcheski, Fort Frances, Ontario, Canada

Application May 2, 1945, Serial No. 591,429

1 Claim. (Cl. 292—170)

1

The present invention relates to new and useful improvements in door locks of a type including a slideable key-actuated locking bolt and a slideable push button actuated latch bolt, and the invention has for its primary object to provide a latch bolt embodying push button means for retracting the same from either side of the door and also embodying means for locking both of said push buttons against latch bolt operating movement.

A further object is to provide a door lock of this character of simple and practical construction, which is efficient and reliable in operation, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like reference numerals refer to like parts throughout, and in which:

Figure 1 is a fragmentary edge elevational view of a door showing the lock mounted in position therein,

Figure 2 is a side elevational view of the lock,

Figure 3 is a side elevational view of the lock encased in the casing with the cover plate removed therefrom,

Figure 4 is a fragmentary transverse sectional view through the lock casing and illustrating one of the push buttons for actuating the latch bolt,

Figure 5 is a fragmentary sectional view of the push button locking means,

Figure 6 is a plan view of the guide plate for one of the push buttons,

Figure 7 is a side elevational view of the rockable locking member for the push buttons,

Figure 8 is an edge elevational view thereof with part of the lock casing shown in section,

Figure 9 is a plan view of one of the push buttons,

Figure 10 is a transverse sectional view taken substantially on a line 10—10 of Figure 9,

Figure 11 is a side elevational view of the spring for the push button locking member, and

Figure 12 is a perspective view of the locking plates for the door bolt.

Referring now to the drawings in detail, wherein, for the purpose of illustration, I have disclosed a preferred embodiment of the invention, the numeral 5 designates the lock case mortised in the edge of a door 6.

Slideably mounted in the case is a door bolt 7 having a notch 8 in its lower edge adapted for

2

receiving a key inserted in the key-hole opening 9 of the case.

A plate 10 is positioned in facing contact at one side of the bolt 7, the plate being pivotally mounted at one end on a pin 11 in the case, and the other end of the plate is adapted for movement across the notch 8 into a position for engagement by the key when inserted in said notch to raise the free end of the plate.

10 The bolt 7 is formed with an upstanding lug 12 on its upper edge and the plate 10 is formed with a laterally projecting stop 13 on its upper edge adapted for engaging the opposite edges of the lug 12 when the bolt 7 is moved into its projected and retracted positions.

A leaf spring 14 is secured at one end in the top of the case 5 and has its free end resting on top of the stop 13 to yieldably urge the plate 10 in its lowermost position.

20 Accordingly, when a key is inserted in the lock and is received in the notch 8 of the bolt 7, the plate 10 will be raised upwardly to release the stop 13 from the lug 12 and the bolt 7 may then be moved into either its retracted or projected positions by the key, and upon removal of the key the plate 10 will then be forced downwardly by the spring 14 with the stop 13 positioned at one edge of the lug 12 to retain the bolt in either of its aforesaid positions.

30 A latch bolt 15 is slidably mounted in the lower portion of the case 5, the front end of the latch bolt being slidably supported on the guide 17, the latch bolt being limited in its projected position by a lug 18 positioned behind the guide.

35 The inner end of the latch bolt is slidably mounted in spaced parallel guides 19, between which a coil spring 20 is positioned and engaging the inner end of the latch bolt to project the same forwardly.

40 A pin 21 rises from the upper edge of the latch bolt 15 and on which a roller 22 is journaled, the roller having a groove 23 extending circumferentially thereof.

Openings 24 are formed in the opposite sides of the case 5 adjacent the roller 22 and through which the inner ends of extensible push buttons 25 are movable, the inner ends of the push buttons being formed with arcuate or cam shaped ends 26 curved to seat in the groove 23 of the roller 22, the push buttons being adapted to engage opposite sides of the roller.

45 The cam shaped ends 26 of the push buttons 25 are slidably mounted in slots 27 of guide plates 28 secured to the outside of the case 5.

50 The outer ends of the push buttons are formed

with heads 29 projecting outwardly through dome-shaped cover plates 30, within which coil springs 31 are positioned for engaging pins 32 carried by the push buttons to project the push buttons outwardly in the position as shown in Figure 4 of the drawings.

Accordingly, upon an inwardly actuated movement of the push buttons, the cam heads 26 will engage the roller 22 forwardly of the roller, whereby to retract the latch bolt 15.

The push buttons 25 may be locked against inward depressing movement by means of a locking bar 33 pivoted intermediate its ends on a pin 34 carried by the case and having one end 35 thereof adapted to be interposed between said cam-shaped ends 26 in the path of the inward movement of the push buttons 25, whereby to function as a stop for the push buttons to prevent engagement thereof with the roller 22.

A socket 36 is formed on one side of the bar 33 adapted for receiving a square shaped shank 37 on a wing head 38 journaled in the case to pivotally actuate the bar 33 for moving the end 35 from the position shown in full lines in Figure 3 to its dotted line position out of the path of the push buttons 25 to permit engagement of the push buttons with the roller 22. The bar 33 is held in either of its aforesaid positions by means of a coil spring 39 mounted on the pin 34 and frictionally holding the bar against idle movement.

It is believed that the details of construction and manner of use of the device will be readily understood from the foregoing without further detailed explanation.

5 What I claim is:

10 A door lock comprising a lock case adapted for mounting on a door, a spring-projected latch bolt slidably mounted in the case, a roller journaled on one side of the bolt, and a pair of push buttons carried by the door upon opposite sides of said latch bolt and including laterally curved heads adapted for engaging said roller to retract the bolt, and a pivoted stop swingable to interpose the same between said push buttons to obstruct movement thereof.
